UNITED STATES PATENT OFFICE.

JOHN TUGGLE, OF NEW MIDDLETON, TENNESSEE.

CURRYING-KNIFE.

SPECIFICATION forming part of Letters Patent No. 227,597, dated May 11, 1880.

Application filed March 24, 1880. (Model.)

To all whom it may concern:

Be it known that I, JOHN TUGGLE, of New Middleton, in the county of Smith and State of Tennessee, have invented a new and useful 5 Improvement in Currying-Knives, of which the following is a specification.

My invention consists in a novel construction and mode of attachment of the blade and stock of a currying-knife, whereby provision 10 is made for adjusting the blade to suit the different kinds of work.

In the accompanying drawings, Figure 1 is a side view of my improved knife. Fig. 2 is a section taken on the line $x x$ of Fig. 1. Fig. 15 3 is an edge view.

Similar letters of reference indicate corresponding parts.

A represents the stock, B the blade, and C the handles at the ends of the blade. The 20 stock is slightly curved, so as to present a concave surface on one side to enable it to be used as a burnisher or flattener.

In the stock A is a straight longitudinal

slot, e, in which the blade B is held. In the center of the blade is a transverse slot, f, and 25 at its ends are notches d. The blade is held in place by means of a screw, g, passing through the stock and through the central slot, f, and two screws, h h, passing through the stock and engaging with the notches d.

By loosening the screws g and h h the blade may be adjusted at different angles of inclination with relation to the stock, and held in place by tightening the screws.

Having thus fully described my invention, 35 I claim as new and desire to secure by Letters Patent—

A currying-knife having its stock A slotted and its blade B adjustable to different positions in said stock, and held in place therein 40 by means of a slot, f, and notches d and screws g and h h, as herein shown and described.

JOHN TUGGLE.
